UNITED STATES PATENT OFFICE.

MICHAEL J. HAW AND GEORGE J. HARTMANN, OF CHICAGO, ILLINOIS.

DESIGN FOR A SCRATCH-PLATE FOR MATCHES.

SPECIFICATION forming part of Design No. 34,686, dated June 25, 1901.

Application filed May 6, 1901. Serial No. 59,057. Term of patent 14 years.

To all whom it may concern:

Be it known that we, MICHAEL J. HAW and GEORGE J. HARTMANN, citizens of the United States, residing at Chicago, in the county of Cook and State of Illinois, have invented and produced a new and original Design for Scratch-Plates for Matches, of which the following is a specification, reference being had to the accompanying drawings, forming part thereof.

Figure 1 is a face view of a scratch-plate, showing our new design; and Fig. 2 is a cross-sectional view taken on line 2 2 of Fig. 1 looking in the direction indicated by the arrows.

As shown in the drawings, the leading or material feature of our design consists of an elongated piece A, having rounded ends and near its edges openings a and two concavo-convex ribs b, extending longitudinally, thus

forming a curved groove c on the face of the 20 piece A or plate. The adjacent surfaces of the ribs b and the bottom of the groove c are formed with transverse corrugations d a slight distance apart.

Having described our invention, what we 25 claim as new, and desire to secure by Letters Patent, is—

The design for a scratch-plate for matches, substantially as herein shown and described.

In testimony whereof we have signed our 30 names to this specification in the presence of subscribing witnesses.

MICHAEL J. HAW.
GEO. J. HARTMANN.
